UNITED STATES PATENT OFFICE

ELIAS KHAYAT, OF BROOKLYN, NEW YORK

CONTROL SWITCH FOR ELECTRIC SEWING MACHINES

Application filed July 29, 1931. Serial No. 553,855.

This invention relates to an electrically controlled power transmission and more particularly to a switch by means of which flow of current to a motor for operating a sewing machine or the like may be controlled and the motor set in motion or stopped.

One object of the invention is to provide a switch of this character which may be mounted beneath a work table and opening or closing of the switch controlled by a foot pedal mounted upon the floor where it may be easily reached by an operator's foot.

Another object of the invention is to so construct the switch that it will normally remain open but may be easily and quickly closed, the switch being further so constructed that when pressure upon a foot pedal is removed the movable contact of the switch will quickly move to an open position and thereby prevent arcing which is injurious to a switch.

Another object of the invention is to provide a switch of this character which is very compact in its construction and will not be in an operator's way when mounted beneath a work bench.

The invention is illustrated in the accompanying drawings wherein:

Figure 1 is a view in elevation showing switches of the improved construction applied to sewing machines such as used in large factories.

Figure 2 is an enlarged view of the switch shown in Figure 1 with the cover of the switch box broken away.

Figure 3 is a sectional view taken vertically through the switch along the line 3-3 of Figure 2.

Figure 4 is a fragmentary sectional view taken along the line 4-4 of Figure 3.

Figure 5 is a view similar to Figure 2 illustrating a modified form of switch.

Figure 6 is a sectional view taken along the line 6-6 of Figure 5.

Figure 7 is a view similar to Figure 5 illustrating another modified form of switch.

Figure 8 is a sectional view taken along the line 8-8 of Figure 7.

In large factories a number of machines such as the sewing machines 1 are mounted upon work tables 2 which are of sufficient

length to support a number of machines and an operator sits in front of each machine. A motor 3 for each machine imparts motion to the same by means of a belt 4 which is trained about pulleys 5 and 6. Current for the motor is supplied by wires 7 which extend through a conduit 8 and from the power wires 7 lead branch wires which extend through arms 9 of the conduit and are connected with plugs 10 for engagement with terminals of the switch boxes 11 one of which is mounted beneath each machine and controlled by a treadle 12 pivotally supported by bearing brackets 13. Each operator places his foot upon the treadle which controls his own machine and may cause it to operate or stop independently of the other machine.

The switch boxes are of duplicate construction and each may be formed as shown in Figures 2, 3 and 4 or as shown in Figures 5 and 6 or Figures 7 and 8. Referring to Figures 2, 3 and 4, it will be seen that the box has a hingedly mounted cover 12 which is slotted as shown at 12 in order that a lever may project outwardly through the cover and also permit the cover to be moved to an open position. One wall of the box is formed with an opening 14 and through this opening extends terminal blades 15 and 16 for engagement by the terminal sockets 10. The terminals 15 and 16 are secured upon a backing 17 consisting of a block of insulating material which is secured in the box 11 in any desired manner and to the terminal 16 is attached a conductor wire 18 forming one wire of a cable 19 extending between the switch box and the motor. The other conductor wire of the cable 19 is indicated at 20 and is attached to a terminal 21 consisting of a strip of conductive material secured upon the backing 17. The base portion 22 of the terminal blade 15 is of greater length than the base of the blade 16 and this base 22 extends to approximately the center of the backing 17 and is provided with a side extension 23 carrying hinged ears 24, serving to pivotally mount a movable contact 25 which is formed of conductive material and has one end extending in overlapping relation to the terminal 21 serving as a stationary contact. finger 26 which projects from the movable contact at one end thereof is of such length that it may be disposed out of engagement with the stationary contact when the movable contact is in the position shown in Figure 3 but when the movable contact is rocked upon its pivot 27 by a spring 28 engaging its other end the finger will be moved towards the stationary contact and have good contacting engagement with the same. The spring serves to urge the finger towards the stationary contact and therefore when pressure upon the movable contact is released the movable contact will be very quickly moved to a closing position.

The lever 29 by means of which the movable contact is to be moved to an opened position is pivotally mounted between posts 30 by a pivot pin or axle 31 and is straddled by a spring 32 formed of resilient wire and having its arm coiled about the pivot pin as shown at 33 and terminating in extensions 34 bearing against abutments 35. Therefore, the lever will be normally held in position to retain the movable contact out of engagement with the stationary contact in opposition to action of the spring 28 and when pull upon the lever is released the spring will return the lever to the position shown in Figure 3 and quickly move the movable contact to an open position. Therefore, arcing will not take place between the two contacts. An abutment pin 36 carried by the posts 30 serves to limit swinging movement of the lever in one direction and prevent it from moving beyond the position shown in Figure 3. In order to reduce frictional binding between the lever and the movable contact there has been provided a roller 37 and by referring to Figures 3 and 4 it will be seen that this roller is provided with a core or sleeve 38 of insulating material through which extends a pivot pin or axle 39.

Therefore, danger of a short circuit will be eliminated. A rod 40 is employed to connect the outer end of the lever with a pin 41 projecting from one side of the treadle 12 and by an inspection of Figure 1 it will be readily seen that when pressure is applied in order to tilt the treadle forwardly pull will be exerted upon the lever and the lever moved about its pivot 31 to force the roller toward the pin carrying end of the movable contact and away from the contact in order that the spring 28 may act upon the movable contact and rock it about its pivot 27 and cause the pin 26 to move quickly into engagement with the stationary contact. The circuit through the motor will then be closed and the motor set in motion in order to operate the sewing machine. When the sewing machine is to be stopped it is merely necessary to remove pressure from the treadle and the spring 32 will return the lever to the position shown in Figure 3 and the roller

will engage the movable contact and quickly move it to an open position. The improved switch will therefore operate in a very efficient manner to control operation of the motor and sewing machine.

In Figures 5 and 6 there has been shown a modified form of switch box but since certain portions thereof are the same as those shown in Figures 2 and 3 corresponding numerals have been used. This is also true of the modified form shown in Figures 7 and 8. The terminal blade 15 has its base 42 somewhat shorter than that shown in Figures 2 and 3 and provided with a side extension 43 carrying ears 44 between which a rocker arm 45 is pivotally mounted upon a pin 46. At its front end the rocker arm has a bill 47 from which extends a pin 48 carrying a roller 49 to engage the beveled outer end of the plunger 50 which is slidably mounted in a housing 51 carried by a stationary contact 52 corresponding to the stationary contact 21 and to which the conductor wire 20 is attached. A spring 53 which is coiled about the stem 54 of the plunger 50 yieldably holds the plunger in an extended position and causes it to have good contacting engagement with the roller when the rocker arm is moved to a circuit closing position by the coil spring 55 disposed between the side extension 43 and the rear end 56 of the rocker arm.

In order to control movement of the rocker arm there has been provided a shaft 57 which extends transversely through the switch box and carries a short lever 58 to which the upper end of the rod 40 is attached. An abutment 59 having arms 60 and 61 is firmly secured in a set position upon the shaft 57 by a set screw 62 and one arm of this abutment extends in overlapping relation to the rear end of the rocker arm 45 while the second arm carries a side pin 63 engaged by one end of a coil spring 64. This spring 64 is disposed about the shaft 57 and has its other end extended as shown at 65 and engaging an abutment pin 66 carried by a side wall of the switch box. It will thus be seen that the spring 64 will yieldably resist rotation of the shaft 57 in one direction and the arm 60 will apply pressure upon the rear end of the rocker arm 45 and move the rocker arm to an open position in opposition to action of the spring 55. When the operator applies pressure to the treadle and exerts pull upon the rod 40 the shaft will be rotated and move the arm 60 away from the rocker arm. As the arm 60 moves away from the rocker arm the spring 55 will exert pressure to move the rocker arm in a direction to cause the roller 49 to engage the plunger 50. Since the plunger is acted upon by the spring 53 a very good contact will be established between the roller and the plunger and the motor circuit will be closed.

In Figures 7 and 8 the rocker arm 67 is

pivotedly mounted between bearing brackets corresponding to the bearing brackets or ears 44 and at its front end is formed with a bill 68 terminating in a blade 69 similar to that used upon knife switches and intended to engage between cooperating blades 70 carried by and forming part of a stationary contact 71 to which the conductor wire 20 is secured. A spring 72 having one end anchored to the backing as shown at 73 and its other end engaged through an eye 74 formed upon the rocker arm serves to draw the rocker arm to a closed position. The rear end of the rocker arm is overlapped by an arm 75 of an abutment 76 corresponding to the abutment 59 and this abutment is also formed with an arm 77 carrying a side pin 78 for engagement by one end of a spring 79 which is coiled about a shaft 80 corresponding to the shaft 57. The other end of the spring 79 bears against an abutment pin 81 and therefore the arm 75 will normally bear against the rear end of the rocker arm 67 and hold the arm in its open position shown in Figure 8. A stem 82 which rises from the side extension 43 serves to engage the rear end of the rocker arm and prevent it from being moved by the arm 75 beyond the position shown in Figure 8. By this arrangement the spring 79 will serve to normally retain the switch open but when pressure is applied to the treadle to draw upon the lever arm 83 and rotate the shaft 80 pressure upon the rear end of the rocker arm 67 will be removed and the spring 72 permitted to quickly move this rocker arm or movable contact to a closed position.

From the foregoing description of the construction of my improved invention, the operation thereof and the method of applying the same to use will be readily understood. It will be seen that I have provided a simple, inexpensive and efficient means for carrying out the objects of the invention.

While I have particularly described the elements best adapted to perform the functions set forth, it is obvious that various changes in form, proportion and in the minor details of construction may be resorted to, without departing from the spirit or sacri-

ficing any of the principles of the invention.

Having thus described the invention, what is claimed is:

1. A switch comprising a box provided with an opening at the side thereof, plug blades passing through said opening, said blades being of conducting material, a contact member pivoted to one blade, a terminal located in the path of movement of one end of the contact member, a spring urging the said end of the contact member toward the terminal, a lever arm movable in engagement with the contact member to space the end thereof from the terminal, a spring for retaining the lever arm at normal position and a treadle connected with the lever arm. 70 75 80

2. A switch comprising a box provided with an opening at the side thereof, plug blades passing through said opening, said blades being of conducting material, a contact member pivoted to one blade, a terminal located in the path of movement of one end of the contact member, a spring urging the said end of the contact member toward the terminal, a lever arm movable in engagement with the contact member to space the end thereof from the terminal, a spring for retaining the lever arm at normal position and a treadle connected with the lever arm, said terminal being spring supported and movable transversely 90 95 of the point of contact.

3. A switch comprising a box provided with an opening at the side thereof, plug blades passing through said opening, said blades being of conducting material, a contact member pivoted to one blade, a terminal located in the path of movement of one end of the contact member, a spring urging the said end of the contact member toward the terminal, a lever arm movable in engagement with the contact member to space the end thereof from the terminal, a spring for retaining the lever arm at normal position and a treadle connected with the lever arm, said terminal being bifurcated and adapted to receive the contact point between the bifurcations. 100 105 110

In testimony whereof I affix my signature.

ELIAS KHYAT.
